UNITED STATES PATENT OFFICE.

SAMUEL S. WALES, OF MUNHALL, PENNSYLVANIA.

CIRCUIT-BREAKER FOR HOISTS.

SPECIFICATION forming part of Letters Patent No. 728,523, dated May 19, 1903.

Application filed February 19, 1903. Serial No. 144,052. (No model.)

To all whom it may concern:

Be it known that I, SAMUEL S. WALES, of Munhall, Allegheny county, Pennsylvania, have invented a new and useful Circuit-
5 Breaker for Hoists, of which the following is a full, clear, and exact description, reference being had to the accompanying drawings, forming part of this specification, in which—

Figure 1 is a diagrammatic view showing
10 the connection for one motor with my im-
proved circuit-breaker and stop-switch. Fig.
2 is a plan view, with the top removed, of a
circuit-breaker. Fig. 3 is a top plan view of
the same. Fig. 4 is a side elevation, and Fig.
15 5 is a detail view of the switch-posts.

My invention relates to the circuit connec-
tions for electric hoists, wherein automatic
stop mechanism is provided which limits the
vertical movement of the hoists in both di-
20 rections.

The object of the invention is to prevent
mishandling of the apparatus and to avoid
accidents from negligence of the operator
and, further, to provide an improved circuit-
25 breaker mechanism and automatic brake.

In the drawings, referring to Fig. 1, 2
represents a motor having a line 3 leading
from one brush to the point 4 of a reversing-
controller. The line 5 connects the other
30 brush of the motor with the point 6 of the
controller. The line 7 connects the end of
the field 8 of the motor with the point 9 of the
stop-switch B, which may be connected by
contact-segment 10 with point 11 of the
35 switch, from which the wire 12 leads to point
13 of the controller. The line 14 connects
the other end of the field 8 with the negative
side of the main line through the fuse-block
15 and switch 16.

40 The point 17 of the controller is connected
by line 18 to the point 19 of the switch B
and through the contact-segment 20, point 21,
wire 22 to the positive side of the line through
the fuse-block 15 and switch 16. These con-
45 nections form a complete circuit throughout
the switch B, the controller A, the armature 2,
and the fields 8 of the motor when the switch
is closed and in its normal position. The
circuit-breaker is provided with a third con-
50 ducting-segment 23, and when the segments
10, 20, and 23 are moved to the position shown
in dotted lines the contact 10 connects the

line 7 with point 24 and through line 25 to the
line 5, there being no connection between the
points 9 and 11 through the segment when in
this position. In such position the contact 20
has broken connection between 19 and 21,
and the contact 23 has moved so that it con-
nects the line 14 through the line 26, points
27 and 28, through the line 29 to line 3. In
this position the path from the main lines is
interrupted between the points 9 and 11 and
19 and 21 of the circuit-breaker, so that power
is no longer transmitted to the motor. At
the same time the armature 2 is short-circuited
65 through its own fields at the points 24 and
9 and 27 and 28 of the circuit-breaker. The
armature connections are also reversed, so
that the motor acts as a generator, since the
current generated will flow in a reverse di-
70 rection through the armature. The effect
of this current will be to retard and stop the
motor, and to prevent too great a rush of cur-
rent I may provide a permanent resistance 30
in the line 29, as shown.

75 The circuit-breaker is tripped by a solenoid-
magnet 31, which is connected with the plus
line through line 32 and points 19 and 21 and
to the minus side through line 33, contact 34,
and line 35 to line 14.

80 In the normal position the switch 36 is
closed, leaving the solenoid-circuit open only
at the contact 34. If the circuit is closed at
34, the solenoid is energized and the circuit-
breaker is tripped, the contact-segments be-
85 ing moved to the positions shown in dotted
lines. In resetting the circuit-breaker the
handle 37 is thrown to the left, which motion
first opens the switch 36 and then moves the
contacts back to their normal position in full
90 lines. It is necessary to hold the handle in
this position until the contact 34 is opened
by running the hoist in a direction opposite
to that which caused the safety device to op-
erate. When the contact 34 is thus opened,
95 the handle may be released and a spring
closes the switch 36. The breaker is then again
ready for action. If the breaker were reset
without opening the circuit at the switch, a
destructive arc would be formed at contact
100 34, since this is opened at comparatively slow
speed.

The preferred construction of the circuit-
breaker and stop-switch is shown in Figs. 2

to 5, inclusive. In these figures the hand-lever 38, having a wooden handle 37, is pivoted upon a pin 40, secured to a swinging switch-box 41, which is keyed to the hollow 5 shaft 42, extending downwardly through the box and carrying within the box a spider 43, with insulating-pieces 44, carrying the contact-segments 10, 20, and 23. The contact-points 9, 11, 24, 21, 19, 27, and 28 are preferably spring-mounted, as shown in Fig. 2, these points coacting with the contact-pieces on the spider.

The switch-box 41 consists of a hollow casting containing at one side a post 45, carrying 15 the contact-pieces 46 and 47, which are insulated from each other and from the post, as shown in Fig. 5. The hand-lever has an extension 48, of insulating material, carrying the circuit-closer or switch-blade 49, which 20 is adapted to make connection between the points 46 and 47 in one position of the lever-handle. The handle is provided with a side lug 50, which engages a spiral spring 51, connected to the adjustable tension-bolt 52. This 25 spring normally holds the lever-handle in the closing position for the blades 46 and 47. The movement of this lever within the switch-box is limited by set-screws 53. The two blades 46 and 47 are connected one with the wire 32 30 and the other with the short wire leading to point 19. These wires lead upwardly through a central hole in the hollow shaft 42 and thence lead to the blades through a groove 35 cut in the switch-box, as shown in Fig. 3.

35 The switch-box itself, which forms the main body of the handle, is provided with a forwardly-extending lug 54, adapted to engage stops 55 to limit its movement, and this switch-body of the handle is normally drawn 40 into open position by a strong spiral spring 56, connected to one of the arms of the spider and also to the adjustable screw-bolt 57. The switch-box is provided with a depending wing 58, which acts as a stop to hold the circuit-breaker in closed position, this stop engaging 45 the end of a lug 59, which projects upwardly from the trunnion of a swinging armature 60. This armature is in the form of a plate, which is normally held open in lifted position by 50 means of a spring 61, engaging a lug on the top plate and also a lug on the armature, as shown in Fig. 3. The upward movement of the armature is limited by a lip or lug 62, which engages the cover-plate when the armature is in the upper position. (Shown in 55 dotted lines in Fig. 4.)

In the operation of this combined circuit-breaker and stop-switch the parts are normally in the closed position shown in the figures. When the circuit is closed at 34, the magnet is energized and the armature 60 is drawn down toward it, thus tripping the latch and releasing the entire handle and switch-box. The spring 56 then turns the hollow 65 shaft 42, and thus opens the circuit-breaker and pulls the entire lever-handle to the right until its stop-piece 54 engages one of the

stops 55. To reset the device, the operator seizes the wooden handle and pushes it toward the left. The first action thus given is 70 to withdraw the blade 49 from between the contact-plates 46 and 47, thus opening the solenoid-circuit. When the pivoted handle portion strikes the stop-screw 53 at the right-hand side, a further pressure on the wooden 75 handle swings the entire handle and switch-box with the hollow shaft 42 with its spider. During this movement the depending wing on the switch-box forces back the latch on the armature until it passes beyond it, when the 80 spring 61 will pull the latch into stopping position. The circuit-breaker is thus closed. The operator then moves the hoist backwardly until the contact 34 is opened and then releases the wooden handle, and the spring 85 51 immediately acts to connect the plates 46 and 47, and thus close the solenoid-circuit. It is therefore clear that the operator is prevented from actuating the circuit-breaker and hand-switch in the wrong manner. He cannot 90 leave the hand-switch open, and the mere act of moving the handle back to its normal position closes and locks the circuit-breaker. If he should fail to open the contact 34 before releasing the wooden handle, the device 95 would at once be again tripped, thus compelling him to again push back the handle and hold the wooden handle until he has opened the contact 34.

The advantages of my invention will be 100 obvious to those skilled in this art, since in prior devices the operator must open the hand-switch, then close the circuit-breaker, and then close the hand-switch, and if he fails to close the hand-switch the safety-circuit will 105 be entirely cut out and would not be operative, and, on the other hand, if he failed to open the hand-switch before closing the circuit-breaker he would burn out the contact 34. By the present system all liability to 110 improper actuating of these parts is removed, since by making them a part of the same lever system by the common handle the operator is prevented from omitting any of the movements or from making them in the 115 improper order.

It will be noted that in addition to thus combining the hand-switch and circuit-breaker to insure their proper movements I employ a stop-switch which exerts a braking 120 action upon the hoist when the contact 34 is closed by reason of short-circuiting the fields of the motor across the armature, thus converting it into a generator. The resistance upon the shaft will thus brake down the movement of the hoist and prevent excess movement by reason of the momentum of the parts. This drift or excess movement in ordinary hoists is usually about three feet, whereas in my system it is less than an inch.

125 Many changes may be made in the form and arrangement of the circuit connections, the combined stop-switch and circuit-breaker, and the other parts without departing from

my invention, since I consider myself the first to connect the hand-switch and circuit-breaker, whether mechanically or otherwise, to insure the correct relative movement of 5 these two devices. This connected system may be used with or without the connection to convert the motor into a generator.

I claim—

1. In hoists, a motor-circuit having a circuit-breaker, a safety-circuit having a hand-controlled switch, and an actuating connection between the circuit-breaker and switch; substantially as described.

2. A hoist having a motor-circuit, a circuit-breaker interposed therein, a stop-switch arranged to convert the motor into a generator to exert a braking action, and mechanism arranged to actuate the stop-switch when the circuit-breaker is actuated; substantially as 20 described.

3. A hoist having a motor-circuit and a combined circuit-breaker and stop-switch arranged as a single instrument and containing mechanism for simultaneously actuating the 25 stop-switch to convert the motor into a generator whenever the circuit-breaker is opened; substantially as described.

4. A hoist having a motor-circuit, a circuit-breaker and stop-switch in said circuit, and 30 mechanism actuated by the hoist and arranged to actuate both the circuit-breaker and the stop-switch at a certain predetermined limit of movement; substantially as described.

35 5. A hoist having a motor-circuit with a circuit-breaker and stop-switch therein, and a safety-circuit containing a hand-controlled switch; substantially as described.

6. A hoist having a motor-circuit containing a circuit-breaker, and a safety-circuit containing a hand-controlled switch, said switch having a connection to the circuit-breaker, arranged to automatically open the safety-circuit while the circuit-breaker is being closed; 40

45 substantially as described.

7. A hoist having a motor-circuit contain-

ing a circuit-breaker, a safety-circuit containing a hand-controlled switch, said switch having a connection to the circuit-breaker arranged to automatically open the safety-circuit 50 while the circuit-breaker is being closed, and mechanism for automatically closing the safety-circuit after the circuit-breaker is closed; substantially as described.

8. In hoists, a motor-circuit having a circuit-breaker, a safety-circuit having a hand-controlled switch, an actuating connection between the circuit-breaker and said switch, and a tripping device arranged to open the circuit-breaker without opening the hand-controlled 60 switch; substantially as described.

9. In hoists, a motor having a circuit-breaker, a safety-circuit having a hand-controlled switch, an actuating connection between the circuit-breaker and switch, a spring 65 arranged to open the circuit-breaker and move the switch without opening said switch, and a lighter spring arranged to hold the hand-switch in closed position; substantially as described. 70

10. In hoists, a motor-circuit having a circuit-breaker, a safety-circuit having a hand-controlled switch, and a handle arranged to open the hand-switch and thereafter in its continuous movement close the circuit-breaker, 75 and mechanism for closing the hand-switch when the handle is released; substantially as described.

11. In hoists, a motor-circuit having a circuit-breaker, a safety-circuit having a hand-controlled switch, an actuating connection between the circuit-breaker and switch, and connections actuated by the circuit-breaker and arranged to convert the motor into a generator when the circuit-breaker is opened; substantially as described. 80

In testimony whereof I have hereunto set my hand.

SAMUEL S. WALES.
